SYLVANIA.

VALVE AND OPERATING MECHANISM FOR INTERNAL-COMBUSTION ENGINES.

1,295,774.

Specification of Letters Patent.

Patented Feb. 25, 1919.

Application filed September 13, 1918. Serial No. 253,895.

To all whom it may concern:

Be it known that we, JAMES VERNE LEWIS and LEVI ROY LEWIS, citizens of the United States, residing at Clarks Summit, in the 5 county of Lackawanna and State of Pennsylvania, have invented new and useful Improvements in Valves and Operating Mechanism for Internal-Combustion Engines, of which the following is a specification.

10 This invention relates to internal combustion engines, particularly to valves and operating mechanism therefor, and has for its object the provision of an internal combustion engine in which each cylinder is provided with a single valve which is continuously rotatable in one direction and provided with a single port adapted to be brought into and out of registration with inlet and outlet ports successively whereby 15 the explosive source may be admitted to and the exhaust gases drawn from the cylinder. An important object is the provision of an internal combustion engine of this character in which each cylinder is provided with 20 a circular recess, wedge-shaped in cross section, concentric of the bore thereof and having disposed therein a sleeve valve also wedge shaped in cross section, the inclination of the side of the recess and the valve 25 permitting adjustment whereby to take up the wear upon the valve and the recess so that the engine may be rendered practically noiseless in operation.

A further object is the provision of an engine of this character in which the circular recess forming the valve seat is surrounded 30 on both its outer and inner sides by water-jackets whereby the valves may be kept cool at all times so as to insure a proper movement thereof without danger of sticking on account of expansion caused by excessive heat.

Another object is the provision of an engine of this character in which the rotary sleeve valves are positively driven whereby 40 to eliminate the necessity for the use of springs, the operation being thus positive and assured.

Still another object is the provision of an 45 engine of this character in which the contacting surface of the engine casting where engaged by the rotary valve is provided with spring pressed packing rings bearing resiliently against the valves whereby a tight

joint will be produced which will prevent 55 any possible leakage of oil.

Still another and important object is the provision of an engine of this character in which means are provided for resiliently urging the wedge-shaped rotary sleeve valve 60 into resilient engagement with the inclined walls of the wedge-shaped recess continually and automatically and without any necessity for manual adjustment except after long 65 service.

Still another and more specific object is the provision of an engine of this character in which all the rotary sleeve valves are positively driven by a single shaft operated from the crank shaft whereby proper synchronism 70 and uniformity of movement of the different valves will be assured.

An additional object is the provision of an engine of this character which will be comparatively simple and inexpensive in manufacture, highly efficient in use, durable in service and a general improvement in the art.

With the above and other objects and advantages in view, the invention consists in 80 the details of construction to be hereinafter more fully described and claimed and illustrated in the accompanying drawings in which:—

Figure 1 is a top plan view of the engine. 85

Fig. 2 is a front elevation thereof.

Fig. 3 is a longitudinal sectional view through one of the cylinders, and

Fig. 4 is a detail cross sectional view therethrough along the line 4—4 of Fig. 3. 90

Referring more particularly to the drawings the numeral 5 designates the crank shaft journaled within the crank case 6 to which is secured the casting 7 including the plurality of cylinders 8. The cylinders may be cast singly or *en bloc*, as preferred, this detail forming no essential part of the present invention. Each cylinder 8 is provided with a bore 9 in which is reciprocable a piston 10 connected by a connecting rod 11 with the crank shaft 5 in the ordinary manner. 95

Each cylinder casting 8 is provided concentrically of the bore 9 with a circular recess 12 which is wedge-shaped in cross section as shown with its smallest width at the bottom. Each cylinder casting is further provided with radially extending inlet and outlet ports 13 and 14, respectively, which 100

105

are disposed 120 degrees apart. An inlet manifold 15 is connected with all the cylinders and communicates with the ports 13, while an exhaust manifold 16 is likewise connected with all the cylinders and communicates with the ports 14.

The circular wedge-shaped recess 12 constitutes the valve seat, and in order that this seat as well as the valve to be hereinafter described may be kept cool at all times, the cylinder castings are provided with water jackets 17 and 18 which are disposed inwardly and outwardly of the recess 12, respectively, as clearly shown. Each cylinder casting is provided in its upper wall above substantially the center of the piston with a threaded opening 19 in which the usual spark plug is disposed for igniting a charge compressed between the piston 10 and the lower surface 20 of the top wall of the cylinder casting. This space constitutes the firing chamber and is designated by the numeral 21. The minimum height of the chamber 21 is substantially equal to the height of the ports 13 and 14 so that the capacity of the firing chamber will be comparatively small so as to economize in the use of fuel while permitting effective compression of a charge. The provision of the spark plug receiving opening substantially centrally above the piston is believed to be an important feature as it provides for the ignition of a charge at substantially the center of the firing chamber. In order that the top wall of the firing chamber may also be kept cool, the water jacket 17 extends within the upper wall of the firing chamber and terminates close to the spark plug opening. This upper portion of the water jacket 17 is designated by the numeral 22.

Each cylinder 8 is provided with a single rotary sleeve valve including a cylindrical portion 23 and a ring-like top portion 24. The cylindrical portion 23 of each valve is wedge-shaped in cross section and conforms to the configuration of the wedge-shaped recess. The ring-like portion 24 of each valve is provided with an outwardly extending flange 25 terminating slightly short of an upstanding flange 26 formed on each cylinder casting.

In order to form a tight fit between the valve and the cylinder casting, a circular groove 27 is formed in the top of the casting at its area of contact with the underside of the top 24 of the valve, and within this groove is disposed a plurality of leaf springs 28 upon which is supported a packing ring 29. The cylinder casting is further provided at its area of contact with the outwardly extending flange 25 of the valve top 24, with a similar groove 30 within which is disposed a plurality of leaf springs 31 supporting a packing ring 32 bearing against the underside of the flange 25. The provi-

sion of these packing rings 29 and 32 insures a proper joint between the valve and the casting so that leakage of oil will be prevented.

Secured upon the top of each cylinder casting is a cylindrical projection 33, the walls of which surround the spark plug. Rotatable upon the projection 33 is a worm wheel 34 from the underside of which extends a plurality of downwardly extending pins 35 which have their lower ends slidably engaged within openings 36 in the top portion 24 of the valve. Coil springs 37 surround the pins 35 and abut against the top of the top portion 24 of the valve and the underside of the worm wheel 34. Suitable studs 38 are threaded into the projections 33 and bear against the upper surface of the worm 34 so as to prevent any upward movement thereof. The resilience of the springs 37 is such as to more than offset the resilience of the leaf springs 28 and 31 so that they will urge the valve downwardly into firm engagement with its seat.

In order to provide means for taking up wear on the valve and its seat, a bearing ring 39 is disposed within the lower end of the recess 12 and is engaged by a plurality of adjusting screws 40 which hold the ring 39 in firm engagement with the lower edge of the cylindrical portion 23 of the valve. When the valve becomes worn so that it no longer fits snugly within its seat, it is merely necessary to loosen the screws 40 whereupon the resilience of the springs 37 will urge the valve downwardly so that its inclined sides will again coöperate with the inclined sides of the recess for forming a tight joint.

Formed in each cylindrical projection 33 is a passage 41 which communicates with the water jacket 22. Secured at the upper end of each cylindrical projection 33 is a coupling 42 which communicates with the passage 41, and secured upon one side of each cylinder casting is a coupling 43 which communicates with the water jacket 18. These couplings 42 and 43 provide outlet means for the inner and outer water jackets 17 and 18 respectively, and are connected with a common outlet manifold 44 leading to the radiator of the motor. At points disposed approximately 120 degrees from the couplings 42 and 43, the cylinder castings are provided with similar coupling members 45 and 46 connected with a common inlet manifold 47 also leading to the radiator. The radiator spoken of is not shown as it is not believed to be necessary for a full comprehension of the invention.

In order that all the valves may be simultaneously rotated, we provide a shaft 48 disposed longitudinally of the cylinder castings and journaled in suitable bearings 49. Above each cylinder, the shaft 48 is provided with a worm 50, the worms 50 meshing with

the worm wheels 34. The shaft 48 may be driven from the crank shaft 5 in any suitable manner, though for the sake of illustration we have shown the crank shaft as provided with a sprocket 51 about which is trained a chain 52 which is in turn trained about a sprocket 53 and carried upon the forward end of the shaft 48. The ratio of the sprockets 51 and 53 is two to one so that the valves will be properly timed.

In the operation of the engine it will be seen that as long as the crank shaft 5 is rotating, the shaft 48 will also be rotated at a speed half that of the crank shaft, whereupon by virtue of the worms 50 and worm wheels 34 the valves will be rotated, bringing the ports 54 therein successively in registration with the ports 13 and 14 for admitting the charge and subsequently permitting the exhaust. In other respects, the operation of the engine is the same as the operation of any ordinary internal combustion engine, the pistons 10 and connecting rods 11 operating in the ordinary manner. In view of the fact that the functions of the different parts have already been described, it is thought that the operation will be obvious without further detailed description.

From the foregoing description and a study of the drawings it will be apparent that we have thus provided an internal combustion engine in which each cylinder is provided with a positively driven rotary sleeve valve which is provided with means for taking up wear upon the valve in order to make the engine practically noiseless and to increase its efficiency by preventing leakage of compression and one in which an efficient cooling system is provided by virtue of the provision of the plurality of inner and outer water jackets surrounding the areas of greatest heat. It will be noted that provision is made for providing resilient packing at the areas of contact of the rotary valve, with the cylinder casting whereby oil leakage will be prevented, and that means is also provided for automatically holding the valves in close engagement with their seats so as to insure an effective operation of the engine.

While we have shown and described the preferred embodiment of the invention, it will of course be readily understood that we reserve the right to make such changes in the form, construction and arrangement of parts as will not depart from the spirit of the invention nor the scope of the subjoined claims.

Having thus described the invention we claim—

1. In an internal combustion engine, a cylinder casting provided with a circular recess concentric with the bore of the cylinder and wedge-shaped in cross section, a valve including a cylindrical portion wedge-shaped

in cross section for conforming engagement within said recess, means for rotating the valve, means for urging said valve resiliently toward the smaller end of said recess, wear ring disposed within the smaller end of 70 said recess and engaging against the lower edge of the valve, and a plurality of adjusting screws threaded through the cylinder casting and engaging the underside of said ring.

75

2. In an internal combustion engine, a cylinder casting having its upper face provided with a recess concentric with the bore of the cylinder and provided with ports intersecting the recess, a valve including a cylindrical portion disposed within said recess and provided with a port adapted to register successively with said first named port, said valve further including a ring-like top portion bearing upon the top of the casting, an 80 outwardly extending flange on said valve at the juncture of its ring-like top portion with its cylindrical portion, said flange bearing upon the top of the cylinder casting, the top surface of the casting at its areas of 85 contact with said ring-like top portion of the valve and said flange being provided with circular recesses, upwardly sprung pressed packing rings disposed within said last named recesses and bearing against 90 the underside of said top portion of the valve and said flange, a rotatable member connected with the top portion of said valve, means for rotating said member and a plurality of spring members engaging said 100 members and said top portion of the valve for holding the valve firmly within said first named recesses.

3. In an internal combustion engine, a cylinder casting provided at its top with a circular recess concentric with the bore thereof and wedge shaped in cross section, a rotary valve including a cylindrical portion wedge shaped in cross section conformingly engaging within said recess, said valve further including a ring like top member, an upstanding cylindrical section on the top of said cylinder casting, a drive member rotatable on said projection, a plurality of pins depending from said drive member and slidably engaged within holes formed in the top of said valve, and a plurality of coil springs disposed about said pins and abutting against the top of the valve and the underside of said drive member.

4. In an internal combustion engine, a cylinder casting provided in its top space with a circular recess concentric with the bore and provided with ports intersecting the recess, a rotary valve including a cylindrical portion disposed within said recess and provided with a port adapted to register successively with said first named ports, said valve further including a ring like top, 125 an upstanding cylindrical projection on said 130

casting concentric with said recess, a worm wheel rotatable on said projection, a drive connection between said worm wheel and the top of the valve, said drive means comprising a plurality of pins extending downwardly from said worm wheel and slideable through holes in the top of the valve, a

driven shaft supported above the casting, and a worm on said shaft meshing with said worm wheel.

In testimony whereof we affix our signatures.

JAMES VERNE LEWIS.
LEVI ROY LEWIS.
